(57) **CLAIM**

The ornamental design for a bidet, as shown and described.

DESCRIPTION

FIG. 1 illustrates a front perspective view of a bidet showing our new design;

FIG. 2 illustrates a front elevational view thereof;

FIG. 3 illustrates a rear elevational view thereof;

FIG. 4 illustrates a left side elevational view thereof;

FIG. 5 illustrates a right side elevational view thereof;

FIG. 6 illustrates a top plan view thereof; and

FIG. 7 illustrates a bottom plan view thereof; and,

FIG. 8 illustrates a front perspective view of the bidet with the cover open for clarity of disclosure.

The broken lines shown throughout the views depict unclaimed portions of the bidet and form no part of the claimed design.
